UNITED STATES PATENT OFFICE.

MONTAGUE H. ROBERTS, OF JERSEY CITY, NEW JERSEY, ASSIGNOR TO AIR REDUCTION COMPANY, INCORPORATED, OF NEW YORK, N. Y., A CORPORATION OF NEW YORK.

METHOD OF DISTRIBUTING GASES.

Application filed October 18, 1918. Serial No. 258,408.

To all whom it may concern:

Be it known that I, MONTAGUE H. ROBERTS, a citizen of the United States, residing at Jersey City, in the county of Hudson, State 5 of New Jersey, have invented certain new and useful Improvements in Methods of Distributing Gases; and I do hereby declare the following to be a full, clear, and exact description of the invention, such as 10 will enable others skilled in the art to which it appertains to make and use the same.

This invention relates to a method of distributing gases and more particularly, such as are intended to be subsequently combined 15 in combustible mixtures, although the invention is in no way limited to use with specific gases.

Among the objects of the invention are the prevention of freezing of moisture carried 20 by the gases, elimination of danger in heating the gas conduit, in the event of freezing, dilution of the escaped gas to prevent the formation of explosive mixtures, and detection of any leakage which may 25 occur.

Further objects and advantages of my invention will be apparent, as it is better understood, by reference to the following specification, when read in connection with 30 the accompanying drawing illustrating one means of carrying my invention into effect, in which Fig. 1 is a schematic view illustrating the distribution of the gas; Fig. 2 is a longitudinal section through a portion of 35 the conduit and Fig. 3 is a section on the line 3—3 of Fig. 2.

While my invention will be described in connection with the distribution of oxygen and acetylene, or ethylene, intended to be 40 combined as combustible mixtures, for use in torches or blow-pipes, it is to be understood that the invention is generally applicable to the distribution of any gases where similar problems arise.

It is usual to convey oxygen and acetylene, or ethylene, under compression in cylinders, which provide a limited quantity of the 45 gases and must be replaced, from time to time, as the cylinders become exhausted. I propose to convey these gases from the source of supply to the various points in a building or plant where the gases are to be utilized in suitable pipes. The gases are compressed in water lubricated compressors, 50 and consequently are practically saturated

with moisture. In freezing weather, therefore, the moisture would normally congeal, eventually fill the pipes and prevent further movement of the gases. Owing to the combustible nature of the gases, it would be 60 highly dangerous to heat them with an open flame, according to the common practice in thawing frozen pipes. Furthermore, in conveying oxygen and acetylene, or ethylene, under pressure in pipes, there is a constant 65 danger of leakage and the formation of explosive mixtures which might become accidentally ignited.

In carrying out my invention, I propose to surround the pipes in which the oxygen 70 and acetylene, or ethylene, are conveyed, with a conduit in which the waste nitrogen from the liquid air machines producing the oxygen is constantly flowing. Referring more particularly to the drawing, 5 indicates a source of oxygen and acetylene, or 75 ethylene, and preferably includes machines for recovering oxygen from the atmosphere, a corresponding quantity of nitrogen being also recovered, which is, of course, of no 80 particular value at the point of production, and which normally leaves the machines at a relatively elevated temperature and is exhausted to the atmosphere. 6 indicates various buildings of a plant, it being 85 understood that the drawing is diagrammatic and merely for the purpose of illustration. From the source of gases 5, a conduit 7 leads through its various branches to the buildings 6 where the gases are to be 90 utilized. The ends of the branches extend through the buildings and are open to permit the nitrogen to be exhausted to the atmosphere, when it has served its purpose.

Within the conduit 7, I provide two pipes 95 8 and 9, one carrying the supply of oxygen, and the other the supply of acetylene, or ethylene. Short branch pipes 10 and 11 extend from the pipes 8 and 9 through the walls of the conduit 7 at various points 100 where the gases are to be utilized, and are provided with controlling valves 12 and 13, and end connections 14 and 15, which permit the connection of torches or other apparatus for the utilization of the gases to the 105 pipes 8 and 9. The pipes 8 and 9 are provided with suitable control valves 14' and 15' near their entrance to the conduit 7.

As will be readily understood, the pipes 8 and 9 within the conduit are completely 110

surrounded by a flowing stream of nitrogen, at a sufficiently elevated temperature, to maintain the gases in a warm condition, which will prevent freezing at any normal atmospheric temperatures, so long as the nitrogen continues to flow. The amount of nitrogen is sufficient to dilute and carry away any possible leakage from the pipes 8 and 9, the combustible gas being so diffused in the nitrogen stream that the formation of explosive mixtures becomes impossible. Should the flow of nitrogen temporarily cease and the pipes 8 and 9 freeze in cold weather, they may be readily thawed by the application of an open flame to the conduit 7, the nitrogen stream preventing the formation of mixtures with any leaking gas which might become ignited through the heating of the conduit. Thawing may also be accomplished by increasing the temperature of the stream of nitrogen or by allowing it to flow for a more or less protracted period.

As additional assurance against possible explosions, it is desirable to determine, from time to time, whether any leakage is taking place, and to accomplish this, I provide, at intervals, in the conduit 7, a pet-cock 16 through which nitrogen may be withdrawn from the conduit 7. The nitrogen thus withdrawn may be readily analyzed and the presence of oxygen or acetylene, or ethylene, in the gas will indicate leakage from the pipes 8 and 9. The point at which this leakage occurs may be readily determined by withdrawing nitrogen from the various pet-cocks 16.

The nitrogen employed in carrying out my invention preferably comes from the oxygen column direct, but may be passed through the intercooler of the compressor of the liquid air machine from which it is delivered at a somewhat higher temperature than that at which it escapes from the column. The nitrogen is absolutely dry and is not, therefore, subject to freezing as are the other gases which are saturated with water vapor. Dry gas is a poor conductor of heat and accordingly the conduit 7 may be located above the ground without danger of freezing the moisture in the gases even in very cold weather.

From the foregoing, it will be readily appreciated that I have devised a method of and means for distributing gases which normally can be distributed only through the medium of cylinders carrying a limited supply thereof, and that my invention not only facilitates the handling of the gases, but greatly decreases the cost of such handling, since expensive cylinders are entirely eliminated. Furthermore, a constant supply of the gases is always available at the point where they are to be utilized and operations are not interrupted by the necessity

of providing a fresh supply of gases in cylinders.

It will be understood that the method of the present invention may be practiced upon other forms of apparatus than that shown herein, and also that various modifications of the method, as well as in the details of construction of the apparatus may be made without departing from the principle of the invention. 75

I claim as my invention:

1. A method of distributing combustible gases which comprises conveying a gas in a conductor and surrounding the conductor with a flowing stream consisting of a relatively large volume of an inert fluid medium to dilute and carry away any gas leaking from the conductor. 80

2. A method of distributing gases which comprises conveying a gas in a conductor and surrounding the conductor with a warm flowing stream of a dry fluid medium to prevent freezing of moisture in the gas carried by the conductor. 85

3. A method of distributing gases which comprises conveying a gas in a conductor and surrounding the conductor with a relatively large volume of a warm dry fluid medium to prevent freezing of moisture in the gas carried by the conductor. 90

4. A method of distributing gases which comprises conveying a gas in a conductor and surrounding the conductor with a flowing stream of an inert fluid medium of relatively greater volume than the volume of the gas conveyed to dilute and carry away any gas leaking from the conductor. 100

5. A method of distributing gases which comprises conveying a gas in a conductor and surrounding the conductor with a flowing stream of nitrogen to dilute and carry away any gas leaking from the conductor. 105

6. A method of distributing gases which comprises conveying a gas in a conductor and surrounding the conductor with a warm flowing stream of nitrogen, the volume of nitrogen being relatively greater than the volume of the gas conveyed to dilute and carry away any gas leaking from the conductor, and to prevent freezing of moisture in the gas carried by the conductor. 110

7. A method of distributing oxygen and a combustible gas which comprises conveying the oxygen and combustible gas in separate conductors and surrounding the conductors with a relatively large volume of an inert fluid medium. 115

8. A method of distributing oxygen and a combustible gas which comprises conveying the oxygen and combustible gas in separate conductors and surrounding the conductors with a flowing stream of a dry fluid medium. 125

9. A method of distributing oxygen and a combustible gas which comprises conveying 130

ing the oxygen and combustible gas in separate conductors and surrounding the conductors with a flowing stream of nitrogen.

10. A method of distributing oxygen and
5 a combustible gas which comprises conveying the oxygen and combustible gas in separate conductors and surrounding the conductors with a body of nitrogen at a temperature sufficiently high to prevent freezing of moisture carried by the oxygen and
10 combustible gas.

11. A method of distributing oxygen and a combustible gas such as acetylene, which comprises conveying the oxygen and combustible gas in separate conductors, and 15 surrounding the conductors with a flowing stream of nitrogen at a temperature sufficient to prevent freezing of moisture carried by the oxygen and combustible gas.

In testimony whereof I affix my signature. 20
